Hamilton Sanders LLP; Ryan A. Schneider(57) **CLAIM**

The ornamental design for a laser cleaning device, as shown and described.

DESCRIPTION

FIG. 1 is a perspective view of our new design for a laser cleaning device;

FIG. 2 is a right side elevational view thereof;

FIG. 3 is a left side elevational view thereof;

FIG. 4 is a front elevational view thereof;

FIG. 5 is a back elevational view thereof; and,

FIG. 6 is a top plan view thereof.

The broken lines in the figures depict portions of the laser cleaning device that form no part of the claimed design.
